UNITED STATES PATENT OFFICE

SIDNEY R. RECTANUS AND KRISTIAN KRONBORG, OF MIDDLETOWN, OHIO, ASSIGNEES
TO THE AMERICAN ROLLING MILL COMPANY, OF MIDDLETOWN, OHIO, A COR-
PORATION OF OHIO

PICKLER

Application filed November 30, 1923. Serial No. 677,629.

Our invention relates to devices used in pickling sheet metal in packs, and more particularly to means for operating the devices which control the movement of the packs to the end that manual labor is eliminated to the largest possible extent.

In the type of pickler wherein a large spider is employed, on which bundles of sheets are held by means of chains, and in which the spider revolves and also dips, so as to drop the sheets into floor vats of pickle liquor, it has always been the practice to move the spider in its rotary motion by hand. The manner in which the spider dips the sheets is by means of a large piston on which it is mounted, this piston being hydraulically pushed up and permitted to move down. Prior to revolving the spider, it has been the practice to provide for a full length stroke of the piston which will lift the bundle carriers clear of the floor tanks whereupon the revolving motion is imparted by operators pulling the spider around by main force, and locating it so as to dip each bundle in the next floor tank, said tanks being located in a circle around the base of the machine.

It is the object of our invention to provide for power means for rotating the spider when it is in its position of highest elevation with the sheet bundles held away from the tanks. Although we do not describe the operation of the piston on such pickling machines, it may be noted that the operator by his control, can apply power to the piston to send it up or permit it to move down, but during the dipping period, that the operator throws in a trip which shuts off the power when the piston has moved a certain distance, and opens up the power when it has moved down to its low point.

We accomplish our object by that certain construction and arrangement of parts to be hereinafter more specifically pointed out and claimed.

45 In the drawings:

Figure 1 is a top plan view of the revolving mechanism for a pickler of the type noted.

Figure 2 is a side elevation of the same.

50 Figure 3 is a side elevation detail of the wall guide device.

Figure 4 is a top plan view of the parts shown in Figure 3.

Figure 5 is a side elevation of a spider pickling machine showing the devices of our invention installed thereon.

55

We have not shown the mechanism for operating the pickler piston, nor the complete spider device. It will be understood that the piston indicated at 1, carries a series of arms 2, in the form of a spider, said arms serving to suspend the chains 2^a in Figure 5 which support bundles of sheets to be pickled. The piston has a movement up and down, as supplied by power under control of the operator, and also a movement upwardly to a stop that brings the piston up higher than it moves in the dipping or up-and-down motion, this higher movement serving to lift the spider arms so that they will lift the bundles of sheets clear of the acid and washing tanks.

In our device we secure on the upper end of the piston so as to move up and down with it, a large bull gear 3. In the cross beams 4 of the building in which the machine is housed, we place a frame 5 of suitable cross beams, which frame supports a journal bearing 6. This bearing or housing is located so that the piston will rise into the aperture 7 thereof when same is thrust up to its high position. In the form illustrated, the details of which are not important, the upper end of the piston as illustrated at 8, is tapered off, and the aperture 7 in the bearing 6, is also tapered off as indicated in Figure 2, so that the bearing serves to center the piston and also to provide a definite stop for its upper movement, thereby locating its upper point.

The power mechanism is shown as energized by a motor 10, having a gear and worm reduction 11 between its shaft and the transverse driven shaft 12. The motor and the supports for the shaft 12 are mounted on the beams 4, above the machine.

90

A bracket 13 is provided having mounting means for the shaft 12 which shaft is equipped with a beveled gear 14. The bracket also mounts the intermeshing bevel gear 15, and holds it against movement.

95

100

other than rotary movement. This gear 15 is mounted fixedly on a shaft 16, that extends also through a split bearing 17, and has a splined spur gear 18 at its lower end beneath the beams 4. This bearing 17 also serves as the upper abutment, and the gear 18 as a lower abutment for a spiral spring 19 mounted over the shaft and tending to hold the gear 18 downwardly. The upper end of the shaft 16 has a nut 20 which bears on the top of the gear 15, limiting the downward movement of the shaft 16.

The gear 18 meshes with the bull gear on the spider piston when the piston is lifted to its high position, and the spring arrangement of the shaft 16 takes up any shocks which might occur due to improper tooth engagement as the bull gear is elevated into mesh.

The operator controls the motor by any desired reversing control switch which starts and stops it, so as to give the desired rotation to the spider when same is lifted up.

In order to give a suitable guide for stopping the rotation of the spider, and enabling its accurate location over the floor tanks, we provide for a wall guide as shown in Figures 3 and 4. A frame 21 is mounted on the wall, and mounts on its outer face a downwardly tapered channel piece 22, extending vertically.

Additional frame bars 23 on each spider arm 2 (such arms being usually a pair of diverging T-bars) serve to mount a projecting bar 24 on the end of which is a roller 25.

When the spider is in its high position the roller clears the top of the tapered channel guide, and as the piston is lowered to bring the spider to its operation position, the roller rides into the wide end of the guide, and is guided by the tapered sides thereof to an exact position in the lower part of the guide. The guide is so placed that when any spider arm structure is located in the guide the carrying chains on the several arms will retain the bundles of sheets directly over the several floor tanks.

This guide device not only indicates to the operator the point to which he must bring the spider in lifting and rotating the same, but does not come into effect until the bull gear is out of mesh with its driving pinion, and thus controls the accuracy with which the spider sinks down to its operating or dipping position.

By the use of the two mechanisms in combination we are enabled to do away with considerable manual labor, and to permit a much quicker alignment of the spider, and also we positively maintain the alignment during the dipping operation, in which the roller moves up and down in the narrower portions of the wall guide.

We do not wish to confine our invention

to the particular details of structure described above, and we do not wish to limit ourselves to the exact type of spider and piston structure which has been indicated in the drawings. We have advisedly omitted a showing of the chains, floor tanks, hydraulic cylinders, and the like, as these have been in familiar use for many years throughout the country in many sheet pickling plants.

Having thus described our invention, what we claim as new and desire to secure by Letters Patent, is:—

1. In a pickling machine of the type having a reciprocating and rotating piston with arms thereon, each adapted to carry a bundle of articles to be pickled, so as to dip said bundles into a series of tanks arranged in a circular formation about the piston as a center, a driving mechanism for the piston to revolve it, comprising a driven member on the piston, and a driving member supported above the piston, in such a position that only when the piston is at the upper end of its movement, will said members come into operative engagement.

2. In a pickling machine of the type having a reciprocating and rotating piston with arms thereon, each adapted to carry a bundle of articles to be pickled, so as to dip said bundles into a series of tanks arranged in a circular formation about the piston as a center, a driving mechanism for the piston to revolve it, comprising a member on the piston, and a driving member supported above the piston, in such a position that when the piston is at the upper end of its movement, said members will enter into operative engagement, and a guide for said piston arranged to engage same, only when the piston is below the upper end of its movement.

3. In a pickling machine of the type having a reciprocating and rotating piston with arms thereon, each adapted to carry a bundle of articles to be pickled, so as to dip said bundles into a series of tanks arranged in a circular formation about the piston as a center, a driving mechanism for the piston to revolve it, comprising a member on the piston, and a driving member supported above the piston, in such a position that when the piston is at the upper end of its movement, said members will mesh, said members comprising a bull gear on the piston, and a power drive gear to mesh therewith, said power driven gear resiliently mounted for the purpose described.

4. In a pickling machine of the type described, the combination with the rotary and reciprocatory piston thereof, of spider arms thereon for retaining bundles of articles which are to be dipped into tanks arranged in a circle about said piston, said piston having centering means for its rotary movement comprising an upwardly tapered guide, and means on the spider arms for engaging in

said guide, said means retaining the piston in centered position, and guiding it thereto in its several rotary positions, but so positioned as to free the piston for rotation when at its upper limit of movement.

5. In a pickling machine of the type described, the combination with the rotary and reciprocatory piston thereof, of spider arms extending radially from the piston, projections from said arms, and fixedly mounted means for engaging said projections on the spider arms, and comprising vertically arranged and upwardly divergent guiding arms, said arms terminating at their upper ends below a point where the projections on the spider arms will be, when the piston is at its upper limit of movement.
